UNITED STATES PATENT OFFICE.

ADOLPH L. DE LEEUW, OF HAMILTON, OHIO, ASSIGNOR TO THE CINCINNATI MILLING
MACHINE COMPANY, OF CINCINNATI, OHIO, A CORPORATION OF OHIO.

VICE.

1,018,035.

Specification of Letters Patent.

Patented Feb. 20, 1912.

Application filed October 4, 1909. Serial No. 520,814.

To all whom it may concern:

Be it known that I, ADOLPH L. DE LEEUW, a citizen of the United States, residing at Hamilton, in the county of Butler and State 5 of Ohio, have invented certain new and useful Improvements in Vises, of which the following is a specification.

My invention relates to a fluid-actuated device for moving one of the jaws for clamping the work, whereby a powerful clamp can be conveniently and quickly made or released.

The object of my invention is to provide a device with a fixed and movable jaw, with 15 a rotatable and longitudinal movable adjusting screw for the movable jaw and fluid pressure mechanism for effecting the final clamp movement of the movable jaw.

Another object of my invention is to provide a vise, with a movable jaw adjustable along a parallel support with a manually controlled adjusting screw for initial adjustment of the movable jaw and fluid pressure mechanism, comprising one or more 25 cylinders and pistons in line with an actuating lever for moving the screw and jaw independent of the manual control for effecting a final clamp or release.

The features of my invention are more 30 fully set forth in the description of the accompanying drawings, forming a part of this specification, in which:—

Figure 1 is a side elevation of my improved device. Fig. 2 is a central vertical 35 section through the same and through one of the cylinders. Fig. 3 is an enlarged section on line $x-x$, Fig. 1. Fig. 4 is a front elevation thereof. Fig. 5 is a section on line $w-w$, Fig. 2. Fig. 6 is a section on line 40 $v-v$, Fig. 2.

As illustrated in the drawings, the vise is applicable to be screwed on the moving carriage or table of a machine tool for clamping the work in position.

One of the characteristics of the vise is 45 to provide means for manually adjusting a movable jaw for initially setting the same relatively to the work to be clamped, and to a position to permit a free insertion or with-

drawal of the work from between the clamping jaws, and effecting the final clamp or release by mechanism operated under fluid pressure for a quick manipulation of the vise. This is especially desirable when the vise is used for holding work on the machine tool in finishing a duplicate number of pieces of work.

1 represents the frame or base of the vise, provided at one end with a stationary jaw 2.

3 represents a slideway, and 4 represents 60 a movable jaw mounted upon the slide-way 3, adapted to be adjusted to and from the stationary jaw 2.

5 represents an adjusting screw, one end of which is provided with a flange 7, seating within a groove formed in the movable jaw 4, forming a revoluble connection therewith. The adjusting screw 5 is provided with a nut 8, supported within a bearing 9, and held against rotation by means of the 70 set screw 10 engaging into an elongated slot 11, formed on the nut 8, this set screw holding the nut against rotation, but permitting the longitudinal movement thereof within its bearings.

12, 13, represent cylinders formed in the frame 1, each provided with a fluid port 14, and an intermediate port 15, leading from one cylinder to the other, see Fig. 6, for equalizing the fluid pressure within the cylinders.

16, 17, represent pistons fitted within the respective cylinders 12, 13, said pistons being preferably of hollow formation, provided with the cap-plates 18, for closing the 85 outer end of said pistons, forming abutments for the movable jaw actuating lever.

19 represents an actuating lever pivotally supported between ears 20, projecting from the frame 1, and provided with spherical 90 bosses, adapted to engage a flange 21, formed on the nut 8, upon each side of the adjusting screw 5.

22 represents the bolts with their stems each projected through an elongated slot 23 in the lower part of lever 19, one provided 95 along the vertical line of each cylinder for engagement with the piston for actuating

the lever 19. The bolts 22 are preferably provided with spherical heads each engaging its respective head-plate 18, forming a pivotal engagement therewith, to afford free movement of the actuating lever 19. The bolts 22 are adjustable in the elongated slot 23, for regulating the movement of the actuating lever, for increasing or decreasing the same, relatively to the given movement 5 of the piston by adjusting the bolts to and from the fulcrum of the actuating lever, varying the leverage.

24 represents an actuating rod projected through an enlarged orifice formed in the actuating lever 19, one end of which is provided with a collar 25, engaging the actuating lever, see Fig. 3, its opposite end provided with a boss 26, slidably mounted with in the bore 27, formed in the frame 1, and 15 preferably intermediate of the cylinders 12, 13; and 28 represents a spring, one end of which engages the boss 26, while the opposite end of the spring engages a collar 29, fixed within the mouth of the bore through 20 which the actuating rod projects and is supported. The spring 28 exerts pressure upon. 25 the actuating rod 24, for swinging the lever 19 automatically in one direction, upon release of the fluid pressure, within the cylinder and returning the pistons to normal 30 position.

In operation, clamping the work between the jaws 2, 4, the movable jaw 4 is adjusted practically up to its clamping position by 35 revolving the screw 5 within the nut, leaving the work free between the jaws, after which the fluid pressure is brought into action, within the cylinders, and against the pistons, forcing the same outward, and through 40 their engagement with the lever 19, swing the same, moving the sleeve 8, screw 5, and movable clutch 4, toward the work to effectively clamp the same. Suitable piping is employed in connection with the ports 14, 45 with valve or valves provided, not shown in the drawings, for controlling the fluid through the cylinder.

Having described my invention, I claim:—

1. In a vise, a pair of jaws, a longitudinally movable sleeve locked against rotation, 50 an adjusting screw having a threaded engagement with said sleeve and connected to one of said jaws, and lever mechanism engaging said sleeve to impart longitudinal movement thereto and to the screw and jaw, 55 whereby the initial adjustment of one jaw relative to the others is made by rotating the screw.

60 2. In a vise, a fixed and a movable jaw, a longitudinally movable nut, an adjusting screw having a threaded engagement with said nut and rotatively connected with said movable jaw for adjusting the movable jaw

relative to the fixed jaw, and means engaging said nut to impart longitudinal movement thereto and to the screw and movable jaw for clamping movements. 65

3. In a vise, a fixed and a movable jaw, a rotatively adjustable screw engaging the 70 movable jaw, a longitudinally movable nut, locked against rotation, engaged with said screw, and pressure devices engaging said nut for actuating the same.

4. In a vise, a fixed and a movable jaw, a 75 rotative adjustable screw engaging said movable jaw for initial adjusting of the movable jaw relative to the fixed jaw, and means locked against rotation and engaged with screw for longitudinally moving said 80 screw and movable jaw independent of its rotative adjustment.

5. In a vise, a fixed and a movable jaw, a rotatably adjustable and longitudinally 85 movable adjusting screw engaging said movable jaw, a longitudinally movable sleeve nut locked against rotation and engaging with said screw and pressure devices engaging said nut for longitudinally moving the same, 90 whereby an initial adjustment of the movable jaw is made relative to the fixed jaw by rotative action of the screw, and a final longitudinal clamping movement, through the actuation of the power devices.

6. In a vise, a base formed with a slide- 95 way, a fixed jaw on said base, a movable jaw slidable thereon, an adjusting screw engaging said movable jaw, a nut engaging said screw longitudinally movable and locked against rotation, whereby said movable jaw 100 can be adjusted relatively to the fixed jaw upon rotating said screw, lever mechanism engaging said nut, means for actuating said lever mechanism to impart a limited longitudinal movement thereto. 105

7. In a vise, a pair of jaws, an adjusting screw engaging one of said jaws for adjusting the same relatively to the second jaw, a longitudinally movable nut locked against rotation engaging said screw, lever mechanism engaging said nut, and pressure controlled means engaging said lever mechanism for actuating the same to impart clamping movements to said adjustable jaw independent of the screw adjustment. 110

8. In a vise, a pair of jaws, an adjusting screw engaging one of said jaws for adjusting the same relatively to the second jaw, a longitudinally movable nut engaging said screw, a lever engaging said nut, pressure 115 controlled means engaging said lever for actuating the same to impart clamping movements to said adjustable jaw independent of the screw adjustment, and means adjustable upon said lever engaging said power controlled means for varying leverage.

9. In a vise, a pair of jaws, an adjusting screw engaging one of said jaws for adjust-

ing the same relatively to the second, a longitudinally movable non-rotatable nut engaging with said screw, lever mechanism engaging with said nut, for moving the same and the screw longitudinally, pressure controlled pistons for actuating said lever mechanism, means adjustable upon said lever mechanism engaging said piston, its position of adjustment controlling its lever-

age movement relatively to the movement of the piston.

In testimony whereof, I have hereunto set my hand.

ADOLPH L. DE LEEUW.
